UNITED STATES PATENT OFFICE

91,059

DESIGN FOR A TOBY OR SIMILAR ARTICLE

Robert G. Eberhard, New Haven, Conn., assignor to The Book and Quill Lending Library and Bookshop, Incorporated, New Haven, Conn., a corporation

Application October 6, 1933. Serial No. 49,410

Term of patent 14 years

To all whom it may concern:

Be it known that I, ROBERT G. EBERHARD, a citizen of the United States, residing at New Haven, in the county of New Haven and State of Connecticut, have invented a new, original, and ornamental Design for a Toby or Similar Article, of which the following is a specification, reference being had to the accompanying drawing, forming part thereof.

Fig. 1 is a front view of a toby showing my new design; and

Fig. 2 is a side view of the same.

I claim:

The ornamental design for a toby or similar article as shown.

ROBERT G. EBERHARD.
